MORRIS D. COHEN, OF NASHVILLE, TENNESSEE.

HUMIDIFIER FOR HOT-AIR FURNACES.

Application filed July 16, 1926. Serial No. 122,957.

My present invention relates generally to hot air furnaces, and more particularly to a humidifier for use in connection therewith having as its primary object the proper 5 moistening of the air to offset the extreme dryness thereof under ordinary circumstances. It is well known that most hot air furnaces have what are commonly known as water pans in connection therewith designed 10 to moisten the air, but it is also well known that these water pans are commonly of little, if any, effectiveness, since an entirely insufficient quantity of water is evaporated in the usual structure to thoroughly moisten the 15 air.

It is the general purpose of my invention to provide a humidifier which will be effective and efficient and it is another and particular object of my invention to provide a 20 humidifier which will be continuously effective and efficient without necessitating periodical replenishment and which will necessitate little, if any, attention.

A further object is the provision of a 25 humidifier which may be easily and quickly controlled so as to supply to the warm air flowing from the jacket of the furnace just the required or desired amount of moisture distributed evenly among the several hot air 30 flues commonly leading from the jackets of furnaces of this type.

With the above in mind my invention resides in the apparatus to be now described with reference to the accompanying drawings 35 which form a part of this application, and in which:—

Figure 1 is a vertical sectional view through a hot air furnace and partly through my improvements with which the 40 furnace is equipped;

Figure 2 is a horizontal sectional view taken through the upper portion of the furnace substantially on line 2—2 Fig. 1 and,

Figure 3 is a detail vertical section 45 through the container and adjacent parts of my improved apparatus taken substantially on line 3—3 of Fig. 2.

Referring now to these figures and particularly to Figs. 1 and 2, I have shown a 50 hot air furnace of substantially the usual type, including an inner fire pot comprising a fire bowl 10 and a dome 11 on the bowl, the furnace also including a jacket 12 surrounding and spaced from the fire pot 55 and from the upper portion of which a series of hot air supply flues 13 radiate.

My invention purposes in a furnace of this type, a humidifier which consists of a generally closed casing 14 disposed within the jacket 12, and adjacent to the fire pot, 60 whose top may be removable so as to permit of ready access to the interior of the casing. The casing 14 is preferably curved or otherwise shaped to conform to the contour of the fire pot so that it may be disposed closely 65 adjacent to the latter and provide for maximum efficiency in so far as the heating of the water within the casing 14 by the radiated heat of the fire pot. The inner wall of the casing 14 may be corrugated or otherwise 70 formed to enhance heat absorption. Generally speaking, the casing 14 is of rectangular shape, and as before stated, this casing is closed except for the vapor outlet tube 15 rising from its top and a water supply pipe 16 leading upwardly in its base, as well as an overflow pipe 17 communicating through the upper portion of one 75 side. The casing may also have a drain pipe 14^a provided with a cut off valve 14^b, as it 80 may be necessary at times to drain and clean the casing. The casing may be supported by attaching the same to the fire pot, or upon legs, and the water supply and drain pipes 85 may be utilized as supporting legs to avoid complication.

Within the casing 14 a feed control ball 18 coacts with the fitting 19 around the upper end of the water supply pipe 20 so as to regulate the level of water within the casing 14 90 under the automatic control of a float 21. This float is shown with its stem 22 fulcrumed within the casing 14 and pivotally connected at 23 to the stem 24 of the ball valve 18.

The vapor outlet pipe 15 rising from the casing 14 is curved as shown at 25 in Fig. 1 over the top of the fire pot to approximately the upper central portion of the hot air chamber 12 where it is closed by a cap 26, and where it is provided with a series of small distributing tubes 27 radiating therefrom, with the outer ends thereof opening into the hot air flues 13 radiating from the upper end of the jacket 12.

Above the casing 14 the vapor supply pipe 15 has a Y-extension or branch 28 leading therefrom as best seen in Figs. 1, 2 and 3. The upper outer end 29 of this branch pipe 28 opens externally through the jacket 12 of the furnace and adjacent to its lower inner end the vapor pipe 15 is provided with a

valve 30 positioned to deflect more or less of the vapor through the branch 28 to the atmosphere so as to thus control the amount passing to the hot air supply flues. In this 5 way the condition or amount of moisture in the air supplied by the furnace may be readily controlled since the valve 30 has a stem 31 projecting horizontally and outwardly through the furnace jacket 12 and provided 10 with an outer handle by means of which it may be readily and conveniently manipulated and adjusted. This handle may, as shown at 32, be a sprocket wheel from which a chain 32^a is extended to the floor 15 above, in use, so as to avoid the necessity of approaching the furnace to regulate moisture of the heat.

It is thus obvious that my invention provides a simple, compact and economical device which may be readily installed in practically all types of hot air furnaces, which will be continuously effective and efficient with little, if any, attention, which is capable of ready adjustment to control moisture of the heat supplied by the furnace, and which will be strong and durable in use, with no complicated parts to get out of order.

It is obvious of course that in the installation of the humidifier as proposed by my 30 invention, the jacket 12 of the furnace may be provided with doors such for instance as indicated at 33 and 34, in Fig. 1, respectively, opposite to the casing 14, and to a cut off valve 35 in the water supply pipe 16 35 leading to the casing so that in case of necessary repair or adjustment ready access may be had to these parts.

I claim:—

1. In a hot air furnace having a fire pot

and a jacket around the fire pot having 40 hot air supply flues leading therefrom, a humidifier including a closed water container mounted within the jacket adjacent to the fire pot and shaped to conform to the contour of the latter, water supply and 45 overflow pipes leading to and from said container, means within the container for automatically controlling the supply of water through said supply pipe to normally maintain the desired level of water in the container, a vapor supply pipe leading from the upper portion of the container into the upper portion of the jacket, a valve controlled branch pipe leading from said vapor supply pipe and opening exteriorly through 50 the jacket, and a series of vapor supply tubes leading from the upper portion of the vapor supply pipe and opening into the hot air supply flues of the jacket.

2. In a hot air furnace having a fire pot 60 and a jacket around the fire pot having hot air supply flues leading therefrom, a humidifier including a closed water container mounted within the jacket adjacent to the fire pot, water supply and overflow pipes 65 leading to and from said container, a vapor supply pipe leading upwardly from the container a series of moist air supply tubes leading from said vapor pipe one for each hot air supply flue, a pipe leading to the atmosphere at its one end and its other end connecting with the vapor pipe, a valve at the point of intersection of said vapor pipe and pipe leading to the atmosphere whereby the 70 degree of intermingling of vapor and atmosphere may be controlled, and means for operating the valve from a remote point.

MORRIS D. COHEN.
